UNITED STATES PATENT OFFICE.

JOHN E. SHUTT, OF GANADO, TEXAS.

PUMP.

No. 924,697.

Specification of Letters Patent.

Patented June 15, 1909.

Application filed March 31, 1908. Serial No. 424,398.

To all whom it may concern:

Be it known that I, JOHN E. SHUTT, a citizen of the United States, residing at Ganado, in the county of Jackson and State of Texas, have invented a new and useful Pump, of which the following is a specification.

This invention relates to double acting pumps for pumping water from deep wells, and has for its object to provide a simple and durable construction of pump of this character which will withstand the most severe conditions of service, and which will be reliable and will continuously elevate a large volume of water, and which can be readily secured in place and removed.

The invention further has for its object to provide an operating mechanism for a double acting pump by means of which a very long stroke will be obtained and the operation carried on in a very efficient manner.

The invention also has for its object certain improved details of construction by means of which the operation of the parts will be facilitated all as hereinafter set forth and claimed.

Referring to the accompanying drawings, Figure 1 is a view in elevation of a pumping apparatus constructed in accordance with this invention, and, also, showing broken away and in vertical section, a portion of a well casing containing the lower ends of the plunger rods and their plungers. Fig. 2 is a plan view showing the construction of one of the rocker levers. Fig. 3 is an enlarged detail view showing the means for automatically oiling the pivotal connection of the rocker arms and levers. Fig. 4 is an enlarged detail view showing the lower end of the upper plunger rod and plunger. Fig. 5 is an enlarged detail view showing the lower end of the lower plunger rod and plunger. Fig. 6 is an inverted plan view of the lower plunger.

The mechanism may be used either with an engine or with a wind-mill pump.

1 is the lower plunger rod adapted to be connected at its upper end to the lower end of the pump rod of a wind-mill or other operating device. 2 is the hollow upper plunger rod having its upper end connected to a cross head 3. The lower plunger rod 1 is secured to a cross head 4 by bolts 5 and extends down through and is movable in the upper plunger rod 2.

Pivots connected to the cross heads 3

and 4 by links 6 and 7 are two rocking levers 8 and 9, mounted to rock upon a pin 10 having its ends secured to the cross beams 11, connected to the wind-mill frame, by means of pairs of yokes 12 having hook ends 13 engaging beneath the cross beams 11 and projecting through the strap 13', and bolted thereto by nuts 14, thereby clamping the ends of the pin 10 securely to the cross beams 11. The rocker levers 8 and 9 are each constructed with two members, as shown in Fig. 2, each member having a central, partly curved portion 15, mounted on the pin 10 and branch arms 16 extending from said central portion 15 and uniting at their outer ends to form sockets 17 in which are pivoted the outer ends of the links 6 and 7. The rocker levers 8 and 9 have their branch arms 16 disposed on the central portion 15 in different planes from each other, whereby the adjacent lower edge 18 of one of said branch arms will be parallel to the adjacent upper edge 19 of the other branch arm. The upper edge 20 of one of the branch arms of each rocker lever, and the lower edge 21 of the other branch arm of each lever taper from the center to their outer ends.

The rocker lever 8, constructed as shown and described, is located within the rocker lever 9 to move therein. The rocker levers made in this way are prevented from binding, and, as shown in Fig. 1, they come quite close together.

When the rocker levers are at the other end of their stroke or opened to the fullest extent, the cross heads are pushed far apart, making a very long stroke which gives a similar long stroke to the plungers.

22 is a stuffing box in the cross head 3, through which extends and moves the lower plunger rod 1.

Means for oiling the pivotal connection of the rocker levers and the links connecting them with the cross head is provided as follows:—23 and 24 are the pins connecting the rocker levers 8 and 9 with the links 6 and 7. The pin 23 is provided with a slot 23' extending partly about said pin, and extending into the link 7 is a pipe 25 having its lower end opening into the hole in which the pin 23 is located. On the top of said pipe 25 is an oil cup 26 distributing the oil to said pin. The pin 23 is held in fixed position by a screw 26' and in the lowest position of the links 7 and rocker levers 8 the end of the slot 23' is out of alignment with the lower end of

the pipe 25 cutting off the flow of oil to the pin 23.

Depending below the pin 23 and communicating with the slot 23' is a branch pipe 27 which when the rocker arms are close together, is disposed immediately above the upper open end of a branch pipe 28 mounted in the outer end of the rocker lever 8 and communicating at its lower end with the 10 hole in which is located the pin 24.

The cup 26 is provided with an air tight cover, not shown, which makes it in effect a vacuum oiler, when the oiler stands in a vertical position, or, in other words, when the 15 links 6 and 7 and rocker levers 8 and 9 are in close together no oil can flow out of the cup 6 as no air can be admitted to take the place of the oil discharged.

When the levers are drawn apart, the oil 20 cup swings outward, air is allowed to enter, the vacuum is relieved, and oil flows out to the bearings below.

It will be seen that when the levers are moving apart, the groove 23' in the pin 23 25 will be brought beneath the lower end of the pipe 25 and permit oil to enter therein. On the return stroke, when the levers return again to the closed position, the pipe 25 is cut off and the oil admitted to the slot 23' 30 passes down the pipe 27 and through pipe 28 to the pin 24. It will thus be seen that only during the opening stroke are the pins 23 oiled, and at the completion of the closing 35 stroke the pins 24 are oiled. It will be noted that the lower faces of the plungers are provided with slightly helical ribs 31 so beveled that when the plunger has moved down through the water, the pressure of the water passing through the openings of the plunger 40 will exert a force tending to turn the plunger to the right or in a direction that would tend to tighten all of the valve threads and also the threads on the pump rod.

45 In order to prevent choking the lower plunger the uprights or standards 32 of said plunger are V-shaped in cross section, the knife edges 33 of the standards contacting with the ball valve 34. By this means sand 50 will be prevented from becoming wedged between the ball valve and the standards, thus avoiding choking the valve. It will be seen that by means of the construction of a double actuating pump as hereinbefore set forth, a

light running pump is provided due to the 55 fact that the rocker arms and rods balance one another. Also, by means of such construction a continuous stream of water can be obtained and the increase of flow of water will be materially greater. By means of this 60 invention, also, the valves of the plunger rods will not become unscrewed, but they will be automatically kept tight. The bearings, also, will be automatically oiled during the stroke of the mechanism. 65

What is claimed is:—

1. In a pump of the class described, a pair of reciprocating plungers arranged to move toward and from each other, a pair of concentric rods connected to said plungers, a 70 stationary shaft having a diametrically disposed passage therethrough, a pair of interfitting rocker levers on said shaft, a pair of sets of links extending from said rocker levers, one set being disposed above said levers and the other set below the same, cross heads 75 forming connections between the links of each set, the innermost plunger rod extending through both cross heads and through the diametrical passage of the shaft and being secured to the uppermost cross head, and the outer plunger rod being secured to the lowermost cross head, substantially as specified. 80

2. In a pump of the class described, a pair 85 of reciprocating plungers, concentric plunger rods carrying the same, a stationary shaft having an opening therethrough, a pair of interfitting rocking levers mounted upon said shaft, upper and lower links pivotally 90 connected to the outer ends of said levers, a cross head connecting the inner ends of the upper links, the inner plunger rod extending through the opening of the shaft and being secured to said cross head, a lower cross head 95 connecting the inner ends of the lower links and connected to the outer plunger rod, and a stuffing box carried by said lower cross head for the passage of the inner plunger rod. 100

In testimony that I claim the foregoing as my own, I have hereto affixed my signature in the presence of two witnesses.

JOHN E. SHUTT.
